UNITED STATES PATENT OFFICE.

WILLIAM ARTHUR WATSON, OF MALDEN, MASSACHUSETTS, ASSIGNOR TO NATIONAL PIANO COMPANY, OF BOSTON, MASSACHUSETTS, A CORPORATION OF MAINE.

PNEUMATIC VALVE MECHANISM.

1,094,351.

Specification of Letters Patent. Patented Apr. 21, 1914.

Application filed February 1, 1912. Serial No. 674,849.

To all whom it may concern:

Be it known that I, WILLIAM ARTHUR WATSON, a citizen of the United States, and a resident of Malden, in the county of Middlesex and State of Massachusetts, have invented certain new and useful Improvements in Pneumatic Valve Mechanism, of which the following is a specification.

This invention relates to valve structures for pneumatically controlled mechanisms, and is especially intended for use in connection with self-playing musical instruments, although the present invention is not limited thereto, as it may be employed in connection with mechanisms other than musical ones, which employ devices actuated by "pneumatics". In mechanisms of this character, as heretofore generally constructed, it has been difficult to inspect and repair the automatic valve mechanisms, because of the necessity of removing other parts in order to gain access to the valves and other contained members. In my Patent 1,059,324, granted April 15, 1913, I have disclosed and claimed a construction of shell which carries the valve devices, which shell is a seamless one, and is independently removable from the piano without disturbing other parts, the shell carrying the valves which control the passages for the individual operation of power pneumatics.

The object of the present invention is to improve the structure of the shell and the valve devices carried thereby in order to facilitate inspection and repair of these most delicate portions of the instrument.

To these ends the invention consists in the construction and combination of parts substantially as hereinafter described and 40 claimed:—

Of the accompanying drawings,—Figure 1 is a sectional elevation of my improved shell unit and valve mechanism, in connection with sufficient other parts of a "self-playing" piano to illustrate the utility of the present invention. Fig. 2 represents a longitudinal section of the metal shell on line 2—2 of Fig. 4, omitting the members inclosed therein. Fig. 3 is an elevation of the shell from the inner end. Fig. 4 is a plan view of the shell. Fig. 5 is an outer end elevation of the shell. Fig. 6 represents a horizontal section of the shell taken on the line 6—6 of Fig. 7. Fig. 7 represents a section of the shell on line 7—7 of Fig. 6.

Fig. 8 represents a section on line 8—8 of Figs. 1 and 7. Fig. 9 is a plan view of the diaphragm or pneumatic block, removed from the shell. Fig. 10 represents a section on line 10—10 of Fig. 9. Fig. 11 represents a section on line 11—11 of Fig. 9. Fig. 12 illustrates one of the valve disks in plan view, and also shows the compound valve disks in section upon their guiding spindle or pin. Fig. 13 is a detail plan of the means for removably holding the disk valve spindle. Fig. 14 represents a section on line 14—14 of Fig. 13. Fig. 15 is a detail front elevation of several shells to show the method of mounting and securing the sections. Figs. 1 and 15 are practically on a scale of full size, the other figures being on a larger scale.

To facilitate description, reference numerals are employed in the drawings to designate tangible parts of the structure while reference letters are employed to designate spaces, passageways, or ports. In Fig. 1, a portion of the frame of the shell mechanism is indicated at 20, and 21 represents one of the connecting members which actuates a sticker of the piano action, said member 21 being actuated by a lever 22 pivotally supported at 23 and pivotally connected at 24 to a vertical link 25 which has an opening indicated by dotted lines to receive a projection or toe 26 that is carried by the lower or movable member of the power pneumatic 27. The structure so far as described is, or may be, similar to that in my application 277,490, referred to and it need be only understood herein, that when the pneumatic 27 is collapsed due to the exhaustion of air therefrom, the member 21 is raised and in the case of a pneumatic piano, a particular hammer of the action is operated. In said Fig. 1 is represented a suitable construction of the tube board or wind chest 28, having tubes, ducts, or windways, and also having a vacuum chamber b as described in my said application. There is of course a power pneumatic 27 for each duct in the wind chest, while the vacuum chamber is continuous for the entire series. Removably connected with each power pneumatic 27 and with the tube-board or wind chest, is a valve-carrying shell 29, which embraces the structure of my present invention, each shell and its valves being as presently described, so located that it controls 110

the communication between its power pneumatic and the vacuum chamber of the wind chest.

As the shells 29 and their contained mechanisms are duplicates of each other, a detailed description of one will suffice. Each shell is formed with a slotted lug 30 at its front end, a screw 31 passing through the slot of such lug into the front end of the upper member of the pneumatic 27, thereby effecting a tight joint with said pneumatic. The sides of the shell 29 are formed with horizontal semi-circular grooves 32 and with flat faced bosses 33 to receive the pressure of the heads of suitable screws or bolts 34 which extend into the front of the wind chest, Figs. 3, 5 and 15. Each screw fits the grooves 32 of two abutting shells, and by the removal of any two of said screws or bolts, the shell 29 between said screws or bolts can be easily withdrawn from position, after removing screw 31. This structure enables said shells to be fitted closely to each other so as to aid in supporting each other and to occupy the least possible space. When a shell has been removed and is to be replaced, the grooves 32 co-act with the screws or bolts 31 which are left in place, in guiding the shell accurately to position, without possibility of any air passage failing to register perfectly. And after the shell has been returned to place, it is so held by the said guiding screws or bolts as to prevent any possibility of the shell shifting vertically. The internal surfaces of the walls corresponding with the grooves 32 present ribs which serve to reinforce the structure. The shell 29 is formed with internal ribs 25 which serve to still further reinforce the shell, and also serve to hold the pneumatic block in place as hereinafter described and with a horizontal partition 36 and a vertical partition 37 (see Figs. 2 and 3). These two partitions meet, as shown in Fig. 2, so as to form passageways between them and the top and front end of the shell as presently described, the rear end of the shell being open and held by the screws or bolts 34 against the front wall of the vacuum chamber of the wind chest 28, suitable packing material 43 being carried by the front wall of the wind chest. The chamber above the front end of the partition 36, Fig. 2, and in front of the partition 37 is divided by integral webs 38 to form between them a passageway *g* and the ends of said passageway are closed as at 39 and 40. Said end closures are preferably plugs of cork or other material in order to facilitate the casting of the shell when made of metal, but by methods well known to founders the end closures 39 and 40 might be integral by the employment of sand cores. In the rear portion of the horizontal partition 36 is an opening *i* across which a bridge 41 extends,

said bridge having a hole 42 to guide the disk valve spindle hereinafter described.

Removably fitted in the bottom of the chamber of the shell and retained thereby by the internal ribs 35, is a block 44 which is preferably made of wood, the upper surface of said block being formed with cavities or concave depressions 45, 46, the relative positions of said cavities and the ports leading thereto being indicated by comparing Fig. 9 with Figs. 10 and 11. Extending over the top of said block is a flexible cover 47, which may be of kid, the edges of said cover extending over the sides of the block and cemented thereto, while an intermediate transverse portion of said cover is secured to said block along the line indicated at 48, so there can be no direct communication between the two cavities 45, 46. The block 44 is a diaphragm-supporting member and constitutes a block-shaped pneumatic which is detachably arranged within the lower chamber of the valve shell. The inner side or end of the supporting member engages the wall or partition 37 which is at an angle to the bottom of the chamber, and the other or outer side or end of said supporting member is in alignment with the open side of the shell so that, when the shell is in place, the supporting member is held endwise so that it cannot shift, even if the ribs 35 were not employed. The ribs 35 serve to keep the diaphragm-supporting member or block 44 in place when the shell is detached, but when the shell is secured in position the diaphragm-supporting member or block is retained in proper position by reason of its ends being held as just described. Secured to the cover 47, above the cavity 46, is a disk 49 which may be of card board or other material cemented to said cover at the center of the said disk, the purpose of said disk being to contact with the lower end of the valve spindle above it as presently described. Secured to the flexible cover 47 above the other cavity 45 is a disk shaped valve block 50 having a transverse aperture 51, the top of said block being preferably faced with leather to constitute a valve. Said block 50 which is an actuator as herein-after explained, is secured to the flexible cover by means of a small metal eyelet 52, having a vent hole 53 communicating with the aperture 51. The connection is effected by pushing the eyelet through a small hole made in the flexible cover, the flange of the eyelet being against the under surface of the flexible material, the block 50 having a vertical hole for the purpose of being then slipped down so as to frictionally hold the block in position upon the flexible cover 47.

The block 44 is formed with two horizontal borings *c*, *e*, which may be termed "blind" ducts, in that they do not permit of the passage of air, because they terminate

respectively in pockets *d*, *f*, formed in the block under the cavities *45*, *46*, in order that the flexible cover above said cavities may be caused to rise and fall, according to the relationship of air pressure above the flexible cover, to the pressure in the ducts *c* and *e* as hereinafter described. It is to be understood, however, that the pocket *d*, when the flexible cover *47* rises, does permit a very slight amount of air to pass through the vent hole *53*.

Mounted in the hole *42* of bridge *41*, and above the disk *49*, is a spindle *54* (see Figs. 1 and 12), the upper end of said spindle being steadied by a device presently described. Said spindle is formed with a collar *55* which is preferably integral therewith as by swaging. Owing to the minuteness of the spindle, its collar, and the disks carried by said spindle, to enable the device to operate in the necessarily small space provided for it, it would be practically impossible to make the collar *55* separate from the spindle and firmly secure it so it would not work loose. But by the integral structure described, absolute reliance can be placed upon the parts being in working conditions at all times. Mounted on the spindle above the collar is a disk *56* having an under facing of leather, and another disk *57* having a leather facing on its upper surface, the two disks *56* and *57* being properly spaced by a loose sleeve *58*. The two disks and the intervening sleeve are sufficiently loose on the spindle, so that the disks may have a slight rocking motion to enable them to automatically closely fit the valve seats presently described. This structure also provides for easy disassociation of the members assembled upon the spindle for the purpose of inspection and regulation.

The holes in the leather facings of the disks fit the spindle so closely as to prevent leakage of air, but still permit the removal and slight rocking motion described. Above the valve block *50* the shell is formed with a rectangular aperture *59* (see Figs. 2 and 6) for the stem *60* of the valve *61* which valve has a suitable facing of leather or other material to normally close the upper end of the aperture *59*, the stem *60* being preferably circular in form so that said stem itself will not entirely obstruct the aperture *59*, although said aperture serves to guide the stem.

The seat for the upper disk valve *57* comprises a removable ring *62* (Figs. 1, 13 and 14) having its inner edge *63* turned upwardly and having its outer edge formed as a flange *64* resting on a seat *65* (Fig. 2) around an opening *66* in the top of the shell. The flange *64* is engaged by the heads of screws *67*, which overlap said flange, the latter having edge recesses or notches *68* so that when the ring is turned to bring the re-

cesses opposite the screws, said ring can be lifted away to enable the spindle *54* and its two disk valves to be removed through opening *66*. The ring *62* has a bridge strip *69* provided with a hole *70* to constitute a bearing for the upper end of the spindle *54*, an extension *71* of said bridge strip serving not only as a handle to enable the ring to be turned but also as a stop to prevent the valve *61* (see Fig. 1) from falling out when the shell is removed and inverted. When the ring is turned away from engagement by screws *67*, said ring can be removed, and then the valve *61* and the spindle *54* and its two disk valves can be lifted out of the shell, and the block *50* can be slid out through the open end of the shell, so that all parts can be quickly examined and repaired if necessary. It is obvious however that the ring can be turned and the valve members removed, without removing the shell from its position upon the vacuum duct or wind chest.

The object of providing the upturned edge *63* of the ring is to prevent "whistling" resulting from an inrush of air between the seat and the upper valve disk *57*. If the inner edge of the ring were not turned upwardly, it would then be so close to the valve disk as to cause a slight whistling noise when said valve disk is leaving its seat.

The operation is as follows:—It being understood that by mechanism well known, there is a constant partial vacuum existing in the chamber *b* or in other words, the air in said chamber is under tension. The passage of the record sheet over the usual tracker board, from which separate tubes or conduits lead to the ducts *a* in the board *28*, causes perforations of said record sheet to admit atmospheric pressure to one or another of the ducts *a*. It is to be understood that each duct *a* communicates through the board *28* with one primary shell. Only one of such communications or passageways is indicated by dotted lines in Fig. 1. Assuming that the one duct indicated at *a* in Fig. 1 has been opened to the atmosphere by the passage of a perforation of the record sheet, such pressure is instantly admitted to the duct *c* (Figs. 8, 9 and 10) resulting in the valve block *50* being lifted because the portion of the flexible cover *47* on which said block *50* is mounted, is subject to the reduced pressure in chamber *m* of the shell below the horizontal partition *36*, said chamber *m* being constantly open to the vacuum or tension chamber *b*. The rise of the block *50* first lifts the valve *61* by means of its stem *60*, and when in its uppermost position the faced top of the block *50* closes the passageway through the aperture *59* around the stem *60*. The block *50* is, therefore, an actuator for the valve *61*. The lifting of the valve *61* admits air under atmospheric pres-

sure to the passageway *g*, between the webs 38, and since the ends of the said passageway are closed, either by cork or integral stops as described, the pressure in said passageway *g* is instantly transmitted through the hole *h* in the vertical partition 37 into the duct *e* of the block 44, thus causing the portion of the flexible cover over pocket *f* to rise, carrying with it the disk 49 and lifting the spindle 54 and the two valve disks 56, 57. This upward movement of the spindle 54 opens the aperture *i* in the partition 36 of the shell and causes the upper valve disk to seat against the bottom of the ring 62. Thus the admission of atmospheric pressure to the chamber *l* above the partition 36 is cut off and communication is established between the chambers *b* and *m* and with chamber *l* and also the passageways *h* between the webs 38 and the inner walls of the shell (see Figs. 6, 7 and 8). Since the passageways *h* communicate with a port *n*, the upper member of the power pneumatic 27, the reduced pressure in the passageways *h* and chamber *l* result in atmospheric pressure actuating the lower member of the power pneumatic so as to cause the operation of the abstract 21 through the connections hereinafter described. After the perforation of the record sheet has passed beyond the opening of the tracker board which communicates with the selected duct *a*, the cutting off of the atmospheric pressure from duct *c* and pocket *d*, permits valve block 50 to instantly descend under the influence of the atmospheric pressure striking the top of the valve 61 as it passes downwardly around the valve stem 60, the vent 53 in the connecting eyelet 52 permitting this to be done. The quick downward movement of the valve block 50 is aided by the fact that the reduced pressure in chamber *m* is communicated through the vent 53 to the pocket *d*. The vent hole 53 is not large enough to permit air to so freely escape through it during the first described or upward movement of the block as to interfere with the lifting of the said valve block. The downward movement of the valve block is also aided by atmospheric pressure on valve 61, tending to cause the stem 60 to push the valve block down. As the valve 61 seats, it cuts off atmospheric pressure from passageway *g* and the descent of valve 50 from its seat against the under side of partition 36 opens communication between passageway *g* and chamber *m* due to the fact that the stem 60 does not closely fit its guiding aperture. This results of course in permitting the portion of the flexible cover over the pocket *f* to drop so that the disk 49 will permit spindle 54 to return to the position shown in Fig. 1 closing the communication between chambers *l* and *m* but opening chamber *l* to atmospheric pressure which is

instantly communicated through passageways *h* and port *n* to the interior of the power pneumatic 27 so that the latter will, through the connection described permit member 21 to descend.

It will now be understood that I have provided a structure of shell unit which may be readily removed from the vacuum chest without disturbing any of the interior adjustments and without risk of affecting its utility. When so removed, its true condition and that of its contained members may be readily disclosed whenever necessary. The structure of the shell although seamless, is such that all of the moving or movable parts may be passed thereinto or removed therefrom, and all of the walls and partitions are integral so as to prevent any possibility of leakage of air, which often occurs in prior structures due to shrinkage or swelling or poor construction when separate pieces of wood or metal are glued or otherwise secured together. Preferably the shell is a light metal casting, but it may be of other material, such as vulcanizable material, the essential features being that it is seamless and consequently air tight when in position in the instrument and capable, first of permitting its contained parts to be removed for examination without disassociating said parts, and second, permitting all of its contained parts to be wholly disassociated for regulating them without dismemberment of the shell conduits and cavities. It will be further understood that I have provided a pneumatic action within the said shell that has the novel feature of a block 50 secured to its actuating diaphragm 45 by means of an eyelet 52 instead of being glued thereto, so that the tendency to stiffen that portion of the diaphragm by adhesive material is eliminated. It will be further understood that the small vent 53 in the top of the eyelet 52 is movable instead of stationary and is therefore self-cleaning. When the vent is stationary, as heretofore, comminuted matter composed of powdered paper worn off from the music sheet, and dust and lint, in time completely plugs the vent, the result being that the notes invariably fail to repeat rapidly. My movable vent is self-cleaning so that it is never necessary to apply a suction pump to the tracker bar to withdraw obstructing matter from the vents.

I claim:—

1. A seamless shell for the control valve of the power pneumatic of a musical instrument, said shell having an open end to register with a vacuum passage or chamber of the instrument, and having means for holding a pneumatic and a valve in proper relative positions, said shell having flat side walls with external grooves whereby a bank of the shells can be guided to and secured in position by fastenings passing through the

spaces provided by opposing grooves of adjacent shells.

2. A seamless shell for the control valve of the power pneumatic of a musical instrument, said shell having an open end to register with a vacuum passage or chamber of the instrument, and having means for holding a pneumatic and a valve in proper relative positions, said shell having flat side walls with external grooves whereby a bank of the shells can be guided to and secured in position by fastenings passing through the spaces provided by opposing grooves of adjacent shells, the shell also having a lug 15 at its front for the purpose described.

3. A seamless shell for the control valve of the power pneumatic of a musical instrument, said shell having an open end to register with a vacuum passage or chamber of the instrument, and having means for containing a pneumatic and a valve in proper relative positions, the side walls of said shell having internal guide ribs, in combination with a pneumatic base slidably engaged with said ribs.

4. A seamless shell for the control valve of the power pneumatic of a musical instrument, said shell having an open end to register with a vacuum passage or chamber of the instrument, and having means for holding a pneumatic and a valve in proper relative positions, said shell having a vertical partition near one end and a horizontal partition connecting with the vertical partition, and webs connecting said partitions with the outer wall of the shell to form a separate passageway between said webs, the ends of said passageway communicating with the interior chamber of the shell.

5. A seamless shell for the control valve of the power pneumatic of a musical instrument, said shell having an open end to register with a vacuum passage or chamber of the instrument, and having means for holding a pneumatic and a valve in proper relative positions, said shell being sub-divided to form an interior chamber, an upper chamber and a plurality of passageways at the front end, and having openings adapted to be controlled by valves.

6. A seamless shell for the control valve of the power pneumatic of a musical instrument, said shell having an open end to register with a vacuum passage or chamber of the instrument, and having means for holding a pneumatic and a valve in proper relative positions, said shell having inner and outer air chambers, the outer chamber having openings in its walls in alinement, a valve having its stem loosely mounted in said openings, and a valve in the inner chamber separate from and adapted to contact with and actuate the said stem.

65 7. A seamless shell for the control valve

of the power pneumatic of a musical instrument, said shell having an open end to register with a vacuum passage or chamber of the instrument, and having means for holding a pneumatic and a valve in proper relative positions, said shell having a vertical partition near one end, and a horizontal partition connecting with the vertical partition, and webs connecting said partitions with the outer wall of the shell to form a 70 separate passageway between said webs, angular apertures being formed in alinement in the said horizontal partition and in the top wall of the shell to admit a valve stem, the ends of said passageway communicating 80 with the interior of the shell.

8. The combination with a shell unit having an interior chamber and ducts or passageways communicating therewith, of a block removably mounted in said chamber, 85 said block having a pair of cavities and ducts leading thereto, a flexible covering material over said cavities, and valves positioned to be actuated by the flexing of said covering material.

9. The combination with a shell unit having an interior chamber and ducts or passageways communicating therewith, of a block removably mounted in said chamber, 95 said block having a pair of cavities and ducts leading thereto, a flexible cover over said cavities, said cover being secured to the block intermediate the cavities to prevent transmission of air from one to the other and valves positioned to be actuated by the 100 flexing of said cover.

10. The combination with a shell unit having an interior chamber and ducts or passageways communicating therewith, of a block removably mounted in said chamber, 105 said block having a pair of cavities and ducts leading thereto, a flexible cover over said cavities, an eyelet having a vent aperture said eyelet having a flange below said cover, a valve block having an aperture communicating with the vent of the eyelet, said valve block being mounted on said eyelet, and a supplemental valve adapted to be actuated by said valve block.

11. The combination with a shell unit 115 having an interior chamber and ducts or passageways communicating therewith, of a block removably mounted in said chamber, said block having a pair of cavities and ducts leading thereto, a flexible cover over 120 said cavities, a spindle having a valve disk, and adapted to be actuated by a portion of the cover over one of said cavities, a valve block carried by the portion of the cover over the other cavity and a supplemental 125 valve adapted to be actuated by said valve block.

12. The combination with a shell unit having an opening, of a valve of less area than the opening to enable it to be removed there-

through, and a valve seat removably fitted to said opening, said valve seat comprising a ring having notches, the shell having members to engage the ring when the latter is turned to carry its notches away from said members.

13. The combination with a shell unit having an opening, of a valve of less area than the opening to enable it to be removed therethrough, and a valve seat having a handle, said valve seat being rotatably mounted relatively to said opening, and having notches, the shell having retaining members to engage portions of the valve seat at the sides of said notches.

14. The combination with a shell unit having an opening, of a valve of less area than the opening to enable it to be removed therethrough, a valve seat comprising a ring having notches and having a bridge provided with an aperture, said bridge having an extension to form a handle, the shell having members to engage the ring when the latter is turned to carry its notches away from said members, the valve including a spindle mounted in the opening of the bridge.

15. The combination with a shell unit having a horizontal partition, the partition and the top of the shell having two pairs of openings in alinement, an external valve having a stem extending down through one pair of openings, a spindle having two valve disks of less diameter than the upper one of the other pair of openings, a ring shaped seat for the upper valve disk, said ring-shaped seat being removably connected with the top of the shell and an extension from said ring-shaped seat over the external valve to act as a stop for the latter.

16. In a primary valve of the character herein described, the combination with the valve block and flexible cover, of a metal eyelet securing the said valve block to the cover.

17. In a primary valve of the character described, the combination with the valve block and the flexible cover, of a metal eye-

let securing the valve block to the cover and having a small aperture forming an air vent. 50

18. A pneumatic action for musical instruments embodying, in its construction, a valve shell having a chamber open at one side thereof, the wall of said chamber opposite said opening being at an angle to 55 the bottom of said chamber, and a diaphragm-supporting member detachably arranged within said chamber, the inner side of said supporting member engaging said wall and the outer side of said supporting 60 member alining with the open side of said shell, whereby said member may be retained in its proper position.

19. A primary valve member having a chamber and a flexible cover for said chamber, an actuator mounted upon said cover, and a metal eyelet securing said actuator to the cover. 65

20. The combination with a shell unit having an interior chamber and a passageway through the roof of said chamber, of a block removably mounted in said chamber, said block having a flexible cover provided with a valve member in close relationship to the lower end of said passageway, the shell having an open side to permit the withdrawal of the block to examine or repair said valve. 70

21. In an automatic musical instrument, a partitioned casing or shell, a block carrying a pneumatic and a valve removably mounted in a chamber in said casing, said parts being combined to form a detachable element which may be removed without disturbing the relationship of said valve and 85 block, the said casing or shell having an opening to expose its interior when the casing is removed from normal or operative position. 80

In testimony whereof I have affixed my 90 signature, in presence of two witnesses.

WILLIAM ARTHUR WATSON.
